SURGICAL APPLIANCE

Albert R. Graham, Pittsburgh, Pa.; Albert E. Graham and Carl F. Graham, executors of Albert R. Graham, deceased

Application October 30, 1947, Serial No. 783,075

5 Claims. (Cl. 128—349)

1

My invention relates, generally, to surgical appliances and, more particularly, to appliances for retaining rubber catheters, drainage tubes, intravenous tubes, and the like, in position on the human body.

In the treatment of certain diseases of the bladder and prostate gland, it is frequently necessary to utilize a rubber tube of a special shape, known as a catheter, to drain the bladder. It is also necessary to provide a temporary drainage tube following certain surgical operations, and rubber tubing is utilized in the process known as intravenous feeding.

The problem of retaining such tubes in their proper position without discomfort to the patients is a difficult one. Many devices have been utilized for this purpose, but none has proven entirely satisfactory.

An object of my invention, generally stated, is to provide a tube retainer of the type hereinafter described which shall be simple and efficient in operation and which may be economically manufactured and installed.

A more specific object of my invention is to provide a tube retainer which will prevent the tube from moving longitudinally as well as transversely.

Another object of my invention is to provide a device suitable for retaining tubes of different types in different positions on the human body.

A further object of my invention is to provide a surgical appliance which may be readily sterilized by any one of the usual methods.

Other objects of my invention will be explained fully hereinafter or will be apparent to those skilled in the art.

In accordance with one embodiment of my invention, a rubber catheter, or similar tube, is retained in position by a spring clamp which is hinged on a metal plate. The clamp has two arms having diverging ends which are engaged by hooks on the metal plate. The tube may be released by disengaging the arms from the hooks and raising the clamp sufficiently for the arms to clear the hooks. The plate may be held in place by a belt or tape around the body.

For a better understanding of the nature and objects of my invention, reference may be had to the following detailed description, taken in conjunction with the accompanying drawing, in which:

Figure 1 is a view, in elevation, of a catheter retainer embodying the principal features of my invention and applied to the body of a patient;

Fig. 2 is an enlarged view, in section, taken along the line II—II of Fig. 1;

2

Fig. 3 is an enlarged view, in elevation, of the catheter retainer;

Fig. 4 is an enlarged view, in section, taken along the line IV—IV of Fig. 3;

Fig. 5 is a view, in elevation, of a modification of the invention, and

Fig. 6 is a view, partly in section and partly in elevation, showing the device illustrated in Fig. 5 utilized to retain an intravenous tube in position on a portion of a patient's body.

Referring now to the drawing, and particularly to Fig. 3, the device shown therein comprises a rectangular plate 10, preferably composed of stainless steel or aluminum, and having a circular opening 11 centrally disposed therein and a rectangular opening 12 disposed near each end of the plate. A spring clamp 13, preferably composed of stainless steel wire, and generally of a U-shape, is releasably hinged to the plate 10 at the base of the U.

As shown most clearly in Fig. 4, a hinge 14 for the clamp 13 may be formed integrally with the plate 10 by cutting and then bending a portion of the plate upwardly and over towards the top surface of the plate to provide an opening 15 between the bent portion 14 and the top surface of the plate 10. The outermost part of the opening 15 is of a diameter slightly less than the diameter of the wire clamp 13, thereby releasably retaining the clamp in the hinge. The end 16 of the hinge portion 14 may be turned upwardly slightly to facilitate the insertion of the clamp 13 into the hinge. Thus, the clamp 13 may be readily removed from the plate 10 for cleaning and sterilizing purposes.

As shown in Fig. 3, the arms of the U-shaped clamp 13 are disposed over the opening 11 and have diverging ends 17. The portions of the arms which lie over the opening 11 may be so shaped that a round rubber tube 18 is compressed to an elliptical shape when engaged by the clamp 13.

The diverging ends 17 are releasably engaged by hooks 19 which are disposed on the plate 10 at the side of the opening 11 opposite the hinge 14. Each hook 19 may be formed integrally with the plate 10 by cutting and then bending a portion of the plate upwardly and over towards the opening left in the plate. The tube 18 may be released from the clamp 13 by compressing the diverging ends 17 toward each other to disengage them from the hooks 19, raising the ends slightly to clear the hooks and then releasing the ends of the arms.

As shown in Figs. 1 and 2, the device illustrated in Figs. 3 and 4 may be utilized to retain

a rubber catheter 18 in position in the human body. The enlarged portion 18a of the catheter 18 may be inserted into the bladder through an opening made by a surgical operation. The tube 18 extends through the opening 11 in the plate 10 and is engaged externally of the body by the clamp 13. As explained hereinbefore, the walls of the tube are compressed slightly by the clamp 13, but not enough to interfere with its drainage function. A gauze pad 21 may be placed underneath the plate 10.

As shown in Fig. 1, an adjustable belt 22 may be attached to the plate 10 by hooks 23 which are inserted into the openings 12 in the plate 10. The belt 22 encircles the waist of the person wearing the device and, if desired, may be held in position by straps or tie members 24 which pass between the legs. In this manner the plate 10 is securely held in its correct position on the body without the use of adhesive tape and sufficient traction may be applied to the catheter 18 to retain its enlarged portion 18a firmly against the interior wall of the bladder.

In the modification of the invention shown in Figs. 5 and 6, in which like parts are designated by the same reference characters as in Figs. 1 to 4, the plate 10 and the clamp 13 are of a somewhat smaller size. As shown most clearly in Fig. 6, a rubber tube 25 having a hollow needle point 26, which may be inserted into an arm or other portion 30 of a patient's body, is retained in position by the plate 10 and clamp 13. A relatively thick gauze pad 27 may be placed underneath the plate 10 which is held in position by straps or cords 28. The cords 28 are inserted through openings 29 in the plate 10 and pass around the arm 30 of the patient. In this manner the tube 25 may be utilized for intravenous feeding of the patient.

From the foregoing description it is apparent that I have provided a surgical appliance which will satisfactorily retain a rubber catheter, drainage tube, intravenous tube or the like in its correct position on the human body without utilizing adhesive tape. The present device is simple in construction and it may be easily sterilized by any one of the usual methods of sterilization. Furthermore, it may be readily manufactured in different sizes as required for different purposes.

Since numerous changes may be made in the construction herein shown and described, and different embodiments of the invention may be made without departing from the spirit and scope thereof, it is intended that all matter contained in the foregoing description or shown in the accompanying drawing shall be interpreted as illustrative and not in a limiting sense.

I claim as my invention:

1. A surgical appliance comprising, a metal plate having an opening therein for receiving a flexible tube, a wire clamp generally of a U-shape

hinged to said plate at the base of the U and having its arms disposed over said opening to engage the tube, and hook means on said plate for releasably engaging the arms of said clamp, said clamp being swingable in a plane perpendicular to the plate when said arms are released from said hook means.

2. A surgical appliance comprising, a metal plate having an opening therein for receiving a flexible tube, a wire clamp generally of a U-shape hinged to said plate at the base of the U and having its arms disposed over said opening to engage the tube, and hook means disposed on said plate to releasably engage the arms of said clamp at the side of said opening opposite the hinge for the clamp, said clamp being swingable in a plane perpendicular to the plate when said arms are released from said hook means.

3. A surgical appliance comprising, a metal plate having an opening therein for receiving a flexible tube, a steel wire clamp generally of a U-shape frictionally releasably hinged to said plate at the base of the U and having its arms disposed over said opening to engage the tube, and hook means on said plate for releasably engaging the arms of said clamp.

4. A surgical appliance comprising, a metal plate having an opening therein for receiving a flexible tube, a steel wire clamp generally of a U-shape frictionally releasably hinged to said plate at the base of the U and having its arms disposed over said opening to engage the tube, said arms having diverging ends, and hook means on said plate for releasably engaging the diverging ends of said arms.

5. A surgical appliance comprising, a metal plate having an opening therein for receiving a flexible tube, a steel wire clamp generally of a U-shape frictionally releasably hinged to said plate at the base of the U and having its arms disposed over said opening to engage the tube, the hinge for said clamp being formed integrally with said plate, and hook means formed integrally with said plate for releasably engaging the arms of said clamp.

ALBERT R. GRAHAM.
